UNITED STATES PATENT OFFICE.

HUGH HOLLEMAN, OF SMACKOVER, ARKANSAS.

GAS BURNER.

Application filed June 1, 1926. Serial No. 113,092.

The invention relates to improvements in gas burners designed primarily for consuming natural gas, and the principal object of the invention is to provide a burner of this type which is extremely simple and inexpensive, yet will be efficient and reliable and will insure proper mixture of air and gas to attain the best results.

One of the most important uses of the burner is in connection with boilers and by proper installation, I have been enabled to overcome the difficulties heretofore prevalent, due to baking of the mud in the mud rings of boilers, which condition is the cause of at least seventy-five per cent of the boiler trouble commonly encountered when gas or natural gas is used as fuel.

With the foregoing in view, the invention resides in the novel subject matter hereinafter described and claimed, the description being supplemented by the accompanying drawing.

Figures 1 and 2 are respectively a side elevation and a top plan view of a burner constructed in accordance with the invention.

Figure 3 is a longitudinal sectional view on line 3—3 of Fig. 2.

Figure 4 is an end elevation.

Figure 5 is a transverse section on line 5—5 of Fig. 3.

Figure 6 is a fragmentary plan view showing the preferred manner of connecting two of the burners for use with a boiler.

The drawings above briefly described may be considered as the preferred form of construction, with the understanding however that within the scope of the invention as claimed, numerous variations may be made.

The numeral 7 designates an elongated burner body of trough-like form, the bottom of this body being designated at 8, while 9 refers to its continuous upstanding side wall. At longitudinally spaced points, the bottom 8 is provided with inlet openings 10 for gas and air, and these openings are preferably surrounded by upstanding nipples 11. By preference, the bottom, side walls and nipples of the body 7 are all cast as a single unit.

Disposed at the open top of the body 7, preferably within the upper portion of the side wall 9, is a baffle 12, said baffle being spaced from said wall to provide a narrow outlet 13 for the mixture of gas and air. This baffle 12 is preferably in the form of a

flat cast plate, and in the preferred form of construction, is provided with downwardly projecting longitudinal flanges 14 which are inwardly spaced from the wall 9 and in the present showing have downwardly projecting leg portions 15 which rest upon the bottom 8. The flanges 14 co-operate with the plate 12 in checking the discharge of gas and air through the outlet 13 and consequently insure thorough mixing and heating of such gas and air before they are discharged for combustion.

Disposed longitudinally under the burner body 7, is a gas supply pipe 16 having outlet orifices 17 in line with the openings 10 and nipples 11. The gas is of course discharged under pressure from the orifices 17 and as it passes through the openings 10 and nipples 11, it induces air to enter through said openings and nipples, and the gas and air become thoroughly mixed under the baffle 12 before they are discharged, as above explained.

In order to get the proper mixture of air and gas, it is necessary to consider climatic conditions and altitude, and in order that the burner may be successfully used under any conditions which may be encountered, I provide for adjusting the pipe 16 toward and from the body 7 and by so doing, I am enabled to vary the amount of air entering the burner body, as occasion may dictate. Preferably, pairs of arms 18 are secured by bolts or the like 19 to the body 7, said arms projecting downwardly from said body and engaging opposite sides of the pipe 16. These arms are provided with longitudinal slots 20, and bolts 21 pass through said slots over and under the pipe 16. This arrangement permits the necessary adjustment of the pipe and after such adjustment, tightening of the bolts will effectively clamp it and the burner body in fixed relation. The arms of each pair may if desired be bent from a single metal bar, as will be clear from Figs. 4 and 5.

I preferably use the burners in groups of two, as indicated in Fig. 6, and when so doing, the pipes 16 of the two burners may be connected with a common supply pipe 22 by means of appropriate piping and connections 23.

Excellent results are obtainable from the details disclosed and they are therefore preferably followed. However, as above stated, variations may be made within the scope of the invention as claimed.

I claim:—

1. A gas burner comprising an elongated trough-like body having spaced air and gas inlets in its bottom, an elongated baffle supported at the top of said body and spaced from the side wall thereof to provide an outlet for the mixture of gas and air, said baffle having downwardly projecting flange means within said body to check the discharge of gas and air and insure thorough mixing thereof, said flange means having downwardly projecting leg portions resting on the bottom of the body, and a gas supply pipe under the body having a plurality of discharge orifices in line with said gas and air inlets.
2. In a gas burner, a burner body, a gas supply pipe arranged beneath said body, adjustable pipe supporting means comprising a pair of arms engaging the opposite sides of said pipe and having therein longitudinally disposed slots, the upper ends of said arms being offset and rigidly secured to said burner body, and bolts passing through said slots on opposite sides of the pipe to clamp said arms against said pipe thereby permitting adjustment of the latter toward and from the burner body.

In testimony whereof I have hereunto affixed my signature.

HUGH HOLLEMAN.
